(57) **CLAIM**

The ornamental design for a pallet changer, as shown and described.

DESCRIPTION

FIG. 1 is a front-left perspective view of a pallet changer showing my new design;

FIG. 2 is a front-right perspective view thereof;

FIG. 3 is a front view thereof;

FIG. 4 is a back view thereof;

FIG. 5 is a right-side view thereof; and,

FIG. 6 is a left side view thereof.

The top and bottom views of the pallet changer are not visible during normal use and form no part of the claimed design.
